Primary Examiner — Messina L Smith*Assistant Examiner* — Elizabeth Borsetti*(74) Attorney, Agent, or Firm* — Bartholomew Law PC; Michael Bartholomew(57) **CLAIM**

The ornamental design for a back scratcher as shown and described.

DESCRIPTION

FIG. 1 is a front, right and bottom perspective view of a back scratcher, showing my new design.
FIG. 2 is a rear, left and top perspective view thereof.
FIG. 3 is a front elevation view thereof.
FIG. 4 is a rear elevation view thereof.
FIG. 5 is a left side elevation view thereof.
FIG. 6 is a right side elevation view thereof.
FIG. 7 is an enlarged top plan view of the back scratcher.
FIG. 8 is an enlarged bottom plan view of the back scratcher.
FIG. 9 is another front, right and bottom perspective view of the back scratcher in an extended state; and,
FIG. 10 is an enlarged view of a portion of the back scratcher shown within the area designated as 10 in FIG. 1.
The dash-dash broken lines depict portions of the back scratcher that form no part of the claimed design. The dot-dash broken lines in FIGS. 1 and 10 depict the boundaries of the enlargements form no part of the claimed design.

1 Claim, 10 Drawing Sheets(56)
